COMBINED HOUSING AND MOUNTING FOR MAGNETIC TAPE RECORD HANDLING AP- PARATUS

Frank J. Reed, Philadelphia, and Lloyd J. Bobb,
Glenside, Pa., assignors to The International
Electronics Company, Philadelphia, Pa., a cor-
poration of Pennsylvania

Application July 29, 1948, Serial No. 147,834

Term of patent 14 years

(Cl. D26—14)

To all whom it may concern:

Be it known that we, Frank J. Reed, a citizen of the United States, residing at Philadelphia, in the county of Philadelphia and State of Pennsylvania, and Lloyd J. Bobb, a citizen of the United States, residing at Glenside, in the county of Montgomery and State of Pennsylvania, have invented a new, original, and ornamental Design for a Combined Housing and Mounting for Magnetic Tape Record Handling Apparatus, of which the following is a specification, reference being had to the accompanying drawings, forming a part thereof.

Figure 1 is a perspective view of a combined housing and mounting for magnetic tape record handling apparatus, showing our new design; and

Figure 2 is a plan view thereof.

The dominant features of our design reside in that portion shown in full lines in the drawing.

We claim:

The ornamental design for a combined hous-
ing and mounting for magnetic tape record han-
dling apparatus, as shown and described.

FRANK J. REED.
LLOYD J. BOBB.
